UNITED STATES PATENT OFFICE.

JOSHUA B. VLIET, OF DETROIT, MICHIGAN, ASSIGNOR OF ONE-HALF TO
CHARLES M. ROEHM, OF DETROIT, MICHIGAN.

BUGGY-TOP ADJUSTER.

SPECIFICATION forming part of Letters Patent No. 703,505, dated July 1, 1902.

Application filed May 2, 1902. Serial No. 105,601. (No model.)

To all whom it may concern:

Be it known that I, JOSHUA B. VLIET, a citizen of the United States, residing at Detroit, county of Wayne, State of Michigan, have invented a certain new and useful Improvement in Buggy-Top Adjusters; and I declare the following to be a full, clear, and exact description of the invention, such as will enable others skilled in the art to which it pertains to make and use the same, reference being had to the accompanying drawings, which form a part of this specification.

My invention relates to an improvement in buggy-top adjusters, and is designed for breaking the joint and lowering the top from the inside.

In the drawings, Figure 1 is a view showing the adjuster attached to a buggy-top. Fig. 2 is an enlarged view of the adjuster, and Fig. 3 is a view showing the bearing-plates separated to disclose the cone-shaped enlargement of the prop-iron.

The object of my invention is to provide a top-adjuster adapted for breaking the joints in lowering the top from the inside, the construction being such that the prop-iron will pass to one side of the bow, the iron being supported in a bearing secured to one side of the bow, but provided with sufficient bearing-surfaces to properly support the iron.

Referring to the letters of reference shown in the drawings, A is the buggy-top, and B and B' are the jointed brace-rods for supporting the top.

C is the prop-iron proper, having an extension formed with an enlarged bearing-surface c, preferably cone-shaped, housed within the separable bearing-plates D and D'.

C' is an operating-lever engaged or formed integral with the prop-iron C. The bearing-plates D and D' have an interiorly-opposing

surface conforming to the enlarged bearing-surface on the prop-iron, and the bearing-plate D has an offset flange d on one side to engage the bow. This flange is recessed on 45 the outer side to permit a similar flange on the bearing-plate D to lie within the recess and be flush with the surface of the flange d. It is of course apparent that the enlarged bearing on the prop-iron need not be necessarily cone-shaped; but I prefer to give it this shape, as the bearing-surface is greatly increased without increasing the width of the bearing.

E is the usual prop-nut to secure the parts 55 against disengagement.

Having thus described my invention, what I claim is—

1. In a buggy-top adjuster, a prop-iron provided with an enlarged bearing-surface, separable bearing-plates adapted to embrace the same, said bearing-plates provided with engaging flanges formed on one side of the bearing and adapted to rest one within the other, the construction being such that the plates 65 forming the bearing may be engaged to one side of the bow, substantially as described.

2. In a buggy-top adjuster, a prop-iron provided with an enlarged bearing-surface, separable bearing-plates adapted to embrace the 70 same, each provided with engaging flanges formed on one side of the bearing-plates, the construction being such that the flanges of the bearing-plates are adapted to be engaged to one side of the bow, substantially as described. 75

In testimony whereof I sign this specification in the presence of two witnesses.

JOSHUA B. VLIET.
